UNITED STATES PATENT OFFICE.

JESSE T. FERGUSON, OF PHILADELPHIA, MISSISSIPPI.

TYPE-WRITER ESCAPEMENT.

1,177,238.

Specification of Letters Patent. Patented Mar. 28, 1916.

Application filed July 31, 1915. Serial No. 43,022.

To all whom it may concern:

Be it known that I, JESSE T. FERGUSON, a citizen of the United States, residing at Philadelphia, in the county of Neshoba and 5 State of Mississippi, have invented a new and useful Type-Writer Escapement, of which the following is a specification.

The device forming the subject matter of this application is adapted to be assembled 10 with typewriter escapements of widely different sorts, for the purpose of increasing the spaces between letters or words at the will of an operator.

The invention aims to provide a novel 15 means whereby, when a letter lever is depressed, a certain spacing will be permitted, it being possible to create a certain spacing by the manipulation of a spacing lever, the construction being such that when the letter 20 lever and the spacing lever are operated simultaneously, an increased spacing will occur.

It is within the province of the disclosure 25 to improve generally and to enhance the utility of devices of that type to which the present invention appertains.

With the above and other objects in view which will appear as the description proceeds, the invention resides in the combination 30 and arrangement of parts and in the details of construction hereinafter described and claimed, it being understood that changes in the precise embodiment of the invention herein disclosed can be made within 35 the scope of what is claimed, without departing from the spirit of the invention.

In the accompanying drawing:—Figure 1 shows in vertical section, one form of typewriter wherewith the device forming the 40 subject matter of this application has been assembled; Fig. 2 is a top plan of the frame of the typewriter, certain portions of the present invention being disclosed; Fig. 3 is a fragmental vertical sectional view showing one form of escapement mechanism 45 which may be embodied in the present invention; Fig. 4 is a vertical sectional view in which the cutting plane lies at right angles to the cutting plane of Fig. 3, the parts delineated in Fig. 3 appearing in Fig. 4; Fig. 5 is a fragmental horizontal section illustrating the stop mechanism whereby the tilting movement of the swinging carrier is arrested and controlled; Fig. 6 50 is a fragmental perspective illustrating a portion of the means whereby the stop por-

tion of the escapement is operated by the action of the spacing lever and the letter lever; Fig. 7 is a sectional view similar to Fig. 1 but showing a modified form of the 60 invention; Fig. 8 is a vertical sectional view showing a portion of the escapement mechanism employed in connection with that form of the invention shown in Fig. 7; Fig. 9 is a cross section of the structure 65 shown in Fig. 8; Fig. 10 is a fragmental top plan showing the platform and the dogs of Fig. 8; Fig. 11 is a perspective view delineating the dogs; Fig. 12 is a perspective showing a modification of the structure 70 shown in Fig. 6; Fig. 13 is a fragmental vertical sectional view similar to Fig. 3 and showing a minor modification of the structure disclosed in Fig. 3.

The device forming the subject matter of 75 this application is adapted to be employed in connection with typewriters of widely different constructions, and in connection with many escapement mechanisms now on the market and well known. In order, 80 however, that the construction and the operation of the present invention may be clearly understood, there is shown in the drawings, a portion of a typewriter comprising a base 1 carrying posts 2 supporting 85 a top 3.

The numeral 4 indicates a carriage mounted to reciprocate on tracks 5 attached to the top 3 of the typewriter frame. By means of connections 6, the carriage 4 is united 90 with a rack bar 7 meshing into a pinion 8 carried by a shaft 9 journaled for rotation in a bearing 10 on the top 3.

Secured to the shaft 9 is an escape wheel 95 11 operating through a slot 12 in the top 3. Brackets 14 depend from the top 3 and carry set screws 15 in which is mounted to swing, in the direction of the arrows A and B of Fig. 4, a carrier 16 which may be in the form of a plate having a forwardly 100 presented crank arm 17. A retractile spring 18 is attached to the carrier 16 and to a projection 19 depending from the top 3. The carrier 16 is adapted to be swung in the direction of the arrow A by the spring 18 105 and is adapted to be swung in the direction of the arrow B by means of the crank arm 17.

Projecting from one of the brackets 14 in a horizontal direction is a rod 20 provided with stops 21 and 21' adapted to coact, respectively, with the forward and rear 110

faces of the carrier 16 to limit the swinging movement thereof in the direction of the arrows B and A, under the action of the crank arm 17 in the one instance and under 5 the action of the spring 18 in the other instance.

The carrier 16 is provided with a pivot element 22 on which is mounted to swing in a direction parallel to the plane defined by 10 the carrier, a rocker 23 of approximately triangular outline. A retractile spring 24 is attached to the rocker 23 and to a suitable projection 25 on the forward face of the carrier 16. The function of the spring 15 24 is to swing the rocker 23 on its pivot 22 to the right as in Fig. 3. Pivoted as shown at 26 to the upper end of the rocker 23 is a main dog 27, adapted to coact with the escape wheel 11. The working end of the 20 main dog 27 is maintained in an uplifted position and in the path of the teeth of the escape wheel 11, by means of a compression spring 28 interposed between the working end of the main dog and the upper edge of 25 the rocker 23. The rocker 23 carries a horizontally projecting stud 29 mounted to move in an arcuate slot 30 formed in the carrier 16.

The invention comprises a bell crank 30 mounted on the swinging carrier 16 to move in a plane substantially at right angles to the plane defined by the carrier. The bell crank above alluded to includes an upright arm 31 interposed in the path of the stud 35 29 on the rocker 23, and a horizontally projecting arm 32 which extends rearwardly from the carrier 16. The bell crank 31—32 is fulcrumed as indicated at 33 on the carrier 16. One end of a leaf spring 34 is secured to the rear face of the carrier 16, the spring 34 extending across the upright arm 31 of the bell crank and constituting a means whereby the said arm is held yieldingingly in the path of the stud 29 on the 45 rocker 23.

Disposed in alinement with the carrier 16 and fulcrumed intermediate its ends as shown at 36 upon one edge of the carrier is a secondary dog 35, the upper, working end 50 of which is adapted to coact with the teeth of the escape wheel 11. A compression spring 37 is interposed between the lower end of the secondary dog 35 and the carrier 16. It may now be stated that, owing to 55 the presence of the springs 28 and 37, the escape wheel 11 may be rotated in the direction of the arrow C in Fig. 3, the dogs 27 and 35 tilting on their respective fulcrums.

60 The operation of the structure as thus far described, will now be set forth and for this purpose, certain of the teeth of the escape wheel 11 have been denoted in Fig. 3 by the numerals 38, 39 and 40. Let it be supposed that the working end of the main

dog 27 is engaged with the tooth 38, the secondary dog 35 lying to one side of the escape wheel 11 as shown in Fig. 4. If the carrier 16 be swung in the direction of the arrow B by means of the crank arm 17, the spring 18 will be put under tension, and the carrier will abut against the stop 21. By this operation, the working end of the main dog 27 will be moved out of engagement with the tooth 38, and the working end of the secondary dog 35 will be brought into the path of the tooth 39, the escape wheel 11 remaining at rest. So soon as the main dog 27 is out of engagement with the tooth 38, the rocker 23 and the main dog 27 will swing to the right in Fig. 3, under the action of the spring 24, the stud 29 moving into abutment with the arm 31 of the bell crank. The working end of the main dog 27 is now in such a 85 position that it may be engaged by the tooth 40 when the carrier 16 swings in the direction of the arrow A. If the crank arm 17 be released, and if the carrier 16 be permitted to swing in the direction of the arrow 90 A under the action of the spring 18 until the carrier engages the stop 21', the working end of the secondary dog 35 will be moved out of the path of the tooth 39 and the working end of the main dog 27 will be 95 moved into the path of the tooth 40, the escape wheel 11 rotating in the direction of the arrow D, and the rocker 23 together with the main dog 27 moving to the left in Fig. 3 until the stud 29 on the rocker 100 23 arrives at the left end of the slot 30 in the carrier 16.

From the foregoing it will be obvious that if at an appropriate time and by a proper means, the bell crank 31—32 can be swung 105 on its fulcrum 33 until the arm 31 no longer lies in the path of the stud 29, the rocker 23 together with the main dog 27 will be permitted to swing to the right in Fig. 3, under the action of the spring 24 beyond 110 the position there shown and, to the right hand end of the slot 30 in the carrier 16, a corresponding increase in the movement of the escape wheel 11 being permitted. An increase in the spacing thus may be 115 brought about at the will of an operator. The means for swinging the carrier 16 and the means for operating the bell crank lever 31—32 will now be set forth in detail.

The numeral 41 designates a character 120 printing lever united by means of a link 63 with the printing mechanism (not shown). The character printing lever 41 is fulcrumed as shown at 42 on the base 1 and is swung upwardly by the action of a 125 retractile spring 43 extended between the base and the lever. A spacing lever 44 is provided and comprises side arms 45, a thrust plate 46 uniting the side arms, at their outer ends, and a connection 47 unit- 130

ing the arms between their forward and rear ends, the connection 47 being preferably in the form of a rigid bar. The rear ends of the side arms 45 of the spacing lever 44 are fulcrumed as indicated at 48 upon the rear portion of the base 1 of the typewriter frame. Retractile springs 49 connect the side arms 45 of the spacing lever with the base portion of the typewriter frame and constitute a means for elevating that end of the spacing lever which embodies the thrust plate 46. Extended beneath the character printing levers 41 and adapted to be operated thereby is a universal bar 50 comprising side arms 51 fulcrumed as shown at 52 upon the base portion 1 of the typewriter frame, the universal bar being swung upwardly by means of retractile springs 53 extended between the side arms of the universal bar and the base portion of the typewriter frame.

The universal bar 50 (Fig. 6) carries an upright 54 provided with a slot 55 in which is mounted to move one end 56 of a connection 57 which may be in the form of a rod, the connection 57 being pivoted as shown at 58 to the crank arm 17 of the carrier 16. Secured to the connection 57 intermediate its ends is an abutment 59. A connection 60, which may be a rod, is attached in any desired manner, as indicated at 61 to the cross bar 47 of the spacing lever 44, the connection 60 terminating in a rearward extension 62 embracing the connection 57 and located above the abutment 59, the construction being such that the connection 57 may move downwardly without actuating the connection 60, and the construction further, being such that when the connection 60 moves downwardly, the extension 62 thereof will coact with the abutment 59 and draw the connection 57 downwardly.

The universal bar 50 carries a post 64 provided with a slot 66. The cross bar 47 of the spacing lever 44 is equipped with a post 65 having a slot 67. Received loosely in the slots 66 and 67 is a rigid rod 68, fulcrumed and poised intermediate its ends as shown at 69 on a flexible element 70, the rear, upper end of which is united with the arm 32 of the bell crank. Extended between the posts 2 at the rear of the machine is a support 71 carrying a transverse bar 72 on the ends of which are mounted pulleys 73 and 74. The flexible element 70 is trained across the top of the pulley 74 and passes beneath the pulley 73.

The carrier 16 is swung in the direction of the arrows A and B in Fig. 4 as follows:—

60 If the character printing lever 41 be pressed downwardly, the universal bar 50 will be depressed, the connection 57 tilting or swinging the carrier 16 through the medium of the crank arm 17. During this operation,

65 the connection 57 slides downwardly through

the extension 62 of the connection 60, and consequently the spacing lever 44 is not depressed. If the spacing lever 44 be depressed, the connection 60, engaging the abutment 59 through the medium of the extension 62, will draw the connection 57 downwardly and swing the carrier 16 through the instrumentality of the crank arm 17. The character printing lever 41 and the spacing lever 44, therefore, may be operated separately, to effect a single spacing. During this operation, however, the arm 31 of the bell crank 32—31 remains in the path of the stud 29 on the rocker 23. The flexible element 70 is not drawn upon to actuate the bell crank lever 31—32 when either the character printing lever 41 or the spacing lever 44 is actuated alone; but when both of the levers 41 and 44 are pressed simultaneously, as may be done by the thumb 85 and finger of an operator, then the flexible element 70 is drawn upon, and the arm 31 of the bell crank lever 31—32 is withdrawn out of the path of the stud 29, an increased space resulting, as will be obvious when the 90 operation of the escapement mechanism is recalled and reviewed.

The manner in which the character printing lever 41 and the spacing lever 44 cooperate with the flexible element 70 will now 95 be described.

When the character printing lever 41 carries the universal bar 50 and the post 64 downwardly, the left hand end of the rod 68 (referring to Fig. 6) is carried downwardly, the right hand end of the rod 68 moving upwardly in the slot 67 of the post 65 which forms a part of the spacing lever 44. The rod 68, therefore, will merely tilt with the point 69 as a fulcrum without pulling downwardly on the flexible element 70. In a similar manner, if the spacing lever 44 is depressed, the post 65 will move downwardly the right hand end of the rod 68 moving downwardly, and the left hand end of the rod 68 moving upwardly in the slot 66 of the post 64 on the universal bar 50. Under such circumstances, the rod 68 will again tilt with the point 69 as a fulcrum, without drawing downwardly on the flexible element 70. When the character printing lever 41 and the spacing lever 44 are depressed simultaneously, then the rod 68, arriving at the upper ends of the slots 66 and 67, is drawn downwardly, the flexible element 70 being pulled upon, and the bell crank 31—32 being tilted, so that the arm 31 of the bell crank will be withdrawn out of the path of the stud 29 on the rocker 23.

A review of the operation of the escapement mechanism shown in Fig. 3, taken in connection with the foregoing description of the operation of the character printing lever 41 and the spacing lever 44 will render it obvious that, at the will of an operator,

an increased space may be provided when the spacing lever 44 and the character printing lever 41 are depressed simultaneously, but not when either of these elements is manipulated alone.

In the modification shown in Fig. 13, two movable dogs 270 and 350 appear, the spring 370 being in a neutral condition. In this form of the invention, the printing mechanism is timed to act while the dog 270 is in the position shown and is engaged with the escape wheel. This modification is introduced to show that the invention is applicable to those escapements which employ two movable dogs, each operating to permit the carriage to move through a half-letter space.

In the modification shown in Fig. 12, the universal bar appears 200, the numeral 201 designating the arms thereof. The connecting bar of the spacing lever is shown at 203. The numeral 204 denotes a post on the universal bar 200, the post 204 having a slot 205 receiving one end 206 of the connection 207, corresponding to the part 57 of Fig. 6. The universal bar 200 is provided with a depending eye 208. The numeral 209 designates the printing lever, the numeral 210 denoting the connection, corresponding to the connection 60, assembled with the bar 203 as shown at 211. Upstanding from the bar 203 is a post 212 having a slot 213. The numeral 214 denotes a rod corresponding to the rod 68, the rod 214 being fulcrumed at 215 on the flexible element 216. One end of the rod 214 is loosely received in the slot 213 of the post 212, the other end of the rod 214 being downbent as shown at 217 and being extended loosely through the eye 208, the lower extremity of the portion 217 of the rod being curved as shown at 218 to extend beneath the universal bar 200.

The structure shown in Fig. 12 operates as does the structure shown in Fig. 6, it being possible to move either the universal bar 200 or the connecting bar 203 downwardly, without actuating the flexible element 216. When, however, the parts 203 and 200 are moved downwardly simultaneously, the flexible element 216 will be pulled downwardly and, like the flexible element 70 actuate the bell crank lever 31-32.

In Figs. 7, 8, 9, 10 and 11 a modified form of the invention is shown. In these figures, and particularly in Fig. 7, parts previously described are designated by reference characters hereinbefore used, with the suffix "a." Projecting from the carriage 4^a are arms 219 extending through the slots 12^a in the top 3^a of the typewriter frame. The arms 219 carry a rack bar 220. Supported on brackets 221 depending from the top 3^a of the typewriter frame is a platform 222. Pivoted at 223 to the platform 222 is a dog 224 having an upstanding working lip 225 adapted to coöperate with the rack bar 220.

The dog 224 is swung in one direction to coöperate with a stop 228 on the platform 222 by means of a spring 226, representing the spring 18, and attached to a projection 227 on the top 3^a of the typewriter frame. The movement of the dog 224 on its pivot 223 in an opposite direction is limited by a stop 229 on the platform 222. Mounted to reciprocate on the dog 224 is a dog 230 passing slidably through an opening 231 formed in the upstanding lip 225 of the dog 224. The dog 230 embodies a laterally offset, upstanding lip 232 adapted to coact with the rack bar 220. In the dog 230, elongated slots 233 are formed, receiving pins 234 which upstand from the dog 224. The dog 230 embodies an upstanding flange 235, and upon the dog 224 there is placed a bracket 236, a compression spring 237 being interposed between the flange 235 and the bracket 236. Projecting laterally from the dog 230 is an arm 238 lying in the path of the reciprocating plunger 240 mounted in a casing 239 depending from the platform 222. For a purpose to be described hereinafter, the upper end of the plunger 240 is beveled at one side, as shown at 241, the lower end of the plunger 240 being loosely pivoted as shown at 242 to a lever 243 fulcrumed on a hanger 244 depending from platform 222 of the typewriter frame. A spring 245 lying within the casing 239 serves to elevate the plunger 240 and to dispose the upper end thereof in the path of the arm 238 of the dog 230.

The operation of the structure shown in Figs. 8, 9, 10 and 11 resembles closely the operation of the structures shown in Figs. 3 and 4 and, with a brief description will be comprehended readily. Let it be supposed that the lip 232 of the dog 230 is in engagement with one of the teeth of the rack bar 220, the arm 238 being in engagement with the plunger 240, as shown in Fig. 10, and the spring 237 being under compression. Under such circumstances, movement of the rack bar 220 to the right will be prevented. If the dog 224 is swung in the direction of the arrow B in Fig. 10, the lip 232 of the dog 230 will move out of engagement with the rack bar 220, and the lip 225 of the dog 230 will move into engagement with the rack bar, the rack bar remaining at rest. When the lip 232 of the dog 230 is moved to one side of the rack bar 220, the dog 230 will be moved to the left, under the action of the spring 237 until the pins 234 arrive at the right hand ends of the slots 233. Then, if the dog 230 be swung in the direction of the arrow A on the pivot 223, the lip 232 of the dog 230 will turn into engagement with the rack bar 220. The rack bar 220 now will move to the right, carrying with it the dog 230, until the arm 238 again engages with the plunger 240. Thus, a cer-

- tain specified amount of spacing may be brought about. When it is desired to double the amount of spacing, the plunger 240 is drawn downwardly, and when the dog 230 5 moves to the right, it will be stopped, not by an engagement between the arm 238 and the plunger 240, but by an engagement between the pins 234 and the ends of the slots 233. Thus, a double spacing will be brought 10 about. Now when the dog 230 has been moved to its extreme right hand position in the manner hereinbefore described, the plunger 240 will be disposed to the left of arm 238, and some means must be provided 15 whereby the arm 238 may move to the left of the plunger 240, as the dog 230 moves to the left. In this connection it is to be noted that the plunger 240 is beveled on its upper end as shown at 241, and is yieldably up- 20 held by the spring 245, the construction therefore being such that as the arm 238 moves to the left along with the dog 230, the arm will depress the plunger and pass there- over. 25 The numeral 247 denotes a shaft extended between the brackets 221, the shaft carrying a pulley 248. Across the pulley 248 passes a flexible element 249 connected with the upper end of the member 57^a, as shown in 30 Fig. 1, the flexible element 249 constituting a means for swinging the dog 224 in the direction of the arrow B of Fig. 10. The flexible element 249 may be intermediately supported on a pulley 250 carried by a 35 hanger 251 depending from the top 3^a of the typewriter frame.
- The flexible element 70^a is connected, as shown in Fig. 8, to the lever 243, and constitutes a means for swinging the lever 40 downwardly on its fulcrum, and for depressing the plunger 240, out of contact with the arm 238 on the dog 230.
- Having thus described the invention, what is claimed is:—
- 45 1. In a typewriter, a carriage; an escapement mechanism coacting with the carriage and including a movable, carriage controlling dog; a movable stop lying in the path of the dog; a printing lever; a spacing lever; a universal bar lying in the path of the printing lever and actuated thereby; means for operatively connecting the universal bar and the spacing lever with the stop, whereby the stop may be moved out 50 of the path of the dog when the printing lever and the spacing lever are operated simultaneously; a primary connection operatively united with the escapement; a secondary connection mounted to slide on the primary connection; an abutment on the primary connection and coacting with the secondary connection; means for uniting the secondary connection with the spacing lever; and a lost motion union between the primary connection and the universal bar. 60
2. In a typewriter, a carriage; an escapement mechanism coacting with the carriage and including a movable, carriage controlling dog; a movable stop lying in the path of the dog; a printing lever; a spacing lever; a universal bar operated by the printing lever; means for operatively connecting the universal bar and the spacing lever with the escapement mechanism whereby the escapement mechanism will be actuated when 70 the printing lever and the spacing lever are moved one at a time; an actuating element connected with the stop; a tiltable member fulcrumed intermediate its ends upon the actuating element; and means for operatively connecting the tiltable member with the universal bar and with the spacing member whereby the tiltable member will swing upon its fulcrum when the printing lever and the spacing lever are separated independently, and whereby the tiltable member will move bodily and operate the actuating element and the stop when the printing lever and the spacing lever are operated simultaneously. 80
3. In a typewriter, a carriage; an escapement mechanism coacting with the carriage and including a movable, carriage controlling dog; a movable stop lying in the path of the dog; a printing lever; a spacing lever; a universal bar operated by the printing lever, the universal bar and the spacing lever including elements provided with slots; a rod having its ends loosely mounted in the slots; and an actuating element on 90 which the rod is fulcrumed, the actuating element being operatively connected with the stop. 95
- In testimony that I claim the foregoing as my own, I have hereto affixed my signature in the presence of two witnesses.
